UNITED STATES PATENT OFFICE

WILLIAM AITKEN, OF LONDON, ENGLAND, ASSIGNOR TO THE RELAY AUTOMATIC TELEPHONE COMPANY, LIMITED, OF LONDON, ENGLAND.

MANUAL AND SEMI-AUTOMATIC TELEPHONE SYSTEM.

1,210,389.

Specification of Letters Patent.

Patented Jan. 2, 1917.

Application filed August 24, 1915. Serial No. 47,115.

To all whom it may concern:

Be it known that I, WILLIAM AITKEN, a subject of the King of Great Britain, residing at Marconi House, Strand, London, England, have invented new and useful Improvements in Manual and Semi-Automatic Telephone Systems, of which the following is a specification.

This invention relates to telephone systems in which the operations are wholly or partly manual and its chief object is to do away with order wire working between manual switchboards and to increase the traffic carrying capacity of junctions between exchanges or switchboards in the same exchange.

According to present practice junction groups between exchanges are arbitrarily divided into sub-groups, usually of about twenty-eight lines, conforming to the carrying capacity of an order wire and to the ability of the operator to deal with the traffic carried by such group. It is, however, recognized that by dividing a number of lines required for carrying a certain traffic into sub-groups which are served separately, the total number of such lines is increased owing to the fact that the traffic variations are greater in small groups than in larger ones. The use of order wires and the subdivisions thereby required of the junctions into small groups consequently reduces the traffic carrying capacity of the junctions.

Another disadvantage due to the arbitrary division by order wires is that the incoming calls are spread over a considerable number of operators' positions and cannot be conveniently concentrated for efficient operating during slack periods.

Attempts to dispense with order wires have already been made, and one such method is to treat the junctions as one group and to fit a lamp at the "A" or originating exchange in connection with the jack of each junction, such lamp being caused to glow at each position to indicate that its associated junction is busy. The lamps of busy junctions then glow during the whole period of a conversation, and the idle lines are those at which no lamp is glowing. Owing, however, to the glare of the lamps, to the amount of current used and to the difficulty of keeping the A jack marked as busy until the B plug has been withdrawn, this arrangement has not found favor.

In semi-automatic systems various electro-mechanical devices have been provided to indicate idle lines by glowing lamps, but these are complicated and expensive. I therefore prefer to use lamps, but in order to overcome the disadvantages just mentioned, I divide the total number of junctions between two exchanges into two main groups; one group, usually the smaller, may be called the common or second choice group. The other or larger group is sub-divided into smaller groups, which may be called the individual or first choice groups. The outgoing junction multiple is also divided into sections of ten or other suitable number of positions and to each section is allotted one individual or first choice group of junctions which may be multiplied in front of every two operators' positions in such section. The first choice group consists of sufficient junctions to carry the normal load of the section with which it is associated. The common or second choice group is multiplied (as is usual) in front of every two operators' positions over the whole outgoing junction multiple and consists of sufficient junctions to carry any traffic above the normal in all the sections. The total traffic carrying capacity of the junctions grouped in this way is practically equal to that of an undivided group adapted for the same traffic.

The result of such a grouping with regard to the aim of this invention is that the number of junctions at each operator's position is considerably reduced without affecting the traffic carrying capacity of the junctions. Consequently, also, the number of lamps in front of an operator is reduced in comparison with the known systems mentioned above, having all junctions multiplied over all positions. I have thereby, to a considerable extent, got over the disadvantage due to the continuous glare of a large number of lamps and the large amount of current used. My invention, however, goes farther and has for its object the provision of lamp indication entirely without the inconvenience of continuously glowing lamps. For that purpose I arrange the lamps in dependence on keys in such a manner that the lamps glow only when an associated key is depressed. Such keys may glow lamps in front of one, two or more operators, as desired. The lamps may also be less in number than the

junctions of a position, means being then provided for connecting the lamps with any desired group of junctions.

In addition to a convenient lamp indication and owing to the absence of order wires, my invention also involves the advantage that the junction lines may be distributed among the B operators in any order and from any of the A positions as best suits the traffic requirements. Instead of being directly associated with plugs at the B positions, the junction lines may end in automatic distributing mechanisms which will connect a line to a plug in front of any idle B operator or connect two operators in rotation or the like.

The manner in which the invention is to be carried out will now be described with reference to the diagrams in which:

20 Figure 1 shows a method of grouping junctions between an exchange A and an exchange B. Fig. 2 shows one method of indicating engaged junctions to an A operator. Fig. 3 shows an alternative method of 25 indicating engaged junctions to an A operator. Fig. 4 shows such indicating means in conjunction with a cord circuit at the B exchange and the method of maintaining a junction busy until the plug is withdrawn 30 at the B exchange. Fig. 5 shows an arrangement of circuits whereby the cord circuit at the B exchange is severed when an A operator takes down the connection.

Fig. 1. Taking for example two exchanges between which there are one hundred junctions and at one of which, the A exchange, there are fifty operators' positions. These are divided into five sections, R, S, T, U, V, each of ten positions. The 40 one hundred junctions are divided into two groups, one of, say, seventy-five, and the other of twenty-five. The seventy-five junctions are further sub-divided into five first choice groups, M N O P Q of, say, fifteen 45 each; that is one to each section, R S T U V of the switchboard, and the group of junctions may be, as in present practice, multiplied at each two positions of its particular section. Only three lines are shown in each 50 of the groups M, N, &c., but it is to be understood that there are fifteen in each group. The remaining twenty-five junctions L are multiplied at each two positions throughout the whole length of the outgoing multiple 55 as second choice lines. In the section R therefore any of the ten operators would be able to route all normal outgoing traffic to the exchange B over the fifteen junctions M and operators in section S would route their 60 normal calls over the groups of junctions N. During the peak load periods some or all of the groups M N O P Q will not be able to cope with the traffic of their respective sections at the A exchange. Only during 65 that period will the common or second choice

group L be used, and only by the operators in the sections in which the individual junctions are not sufficient.

The number of first choice junctions in each section need not be uniform, some having more and some fewer, according to the traffic requirements. The number should be rather less than more than the normal requirements so that during the busy hours every first choice line is engaged and the 70 second choice groups take the peaks of the 75 loads. Under such conditions the groups are equal to a similar number of lines in one group as regards carrying capacity.

Fig. 2 shows a lamp in connection with the jack of each outgoing junction; each operator in the exchange is provided with a key *k* corresponding somewhat to the order wire key at present used. The lamp test may be continuous all around the board, or 80 it may be divided into sections which may or may not correspond to the sections R S T U V, Fig. 1. Common to a section is a relay *a* which on the depression of any key in the section is energized and connects the 85 third or test wire of each of the jacks *j* in the section to the coil of an individual relay *b*. In the jack of any junction which is engaged there will be a plug *p* on the third conductor of which there will be negative potential. Consequently, on an operator pressing a key *k* to test, all the relays *b* of engaged junctions will operate and negative battery will be connected to the lamps *l* 90 associated therewith which will therefore 100 glow. Preferably the keys of the relay *a* are slow to release so that even though an operator remove her finger from the key before inserting a plug into an idle junction she will nevertheless be notified by the 105 subsequent glowing of the lamp if another operator has taken the junction she was about to use.

Fig. 3. To reduce the number of lamps and consequently the height of the junction multiple, the number of busy-indicating lamps may be less than the number of jacks, for example, one strip of lamps may be provided for four exchanges G H J K. Thus, if an operator wishes to test an idle junction to G she will press key *g* which will energize left hand relay *a* to connect the third wires of the G junction to the tester relays *b* and consequently the lamps *l* associated with engaged G junctions will glow. The test lamps in such an arrangement must be individual to each operator's position.

As there must be some time interval between the glowing of the clearing lamp at the B position and the withdrawal of the plug *p* from the jack at the termination of the conversation and after the operator at exchange A has taken down her part of the connection, it is necessary to provide some means whereby a junction tests "engaged" 125 130

until the plug is withdrawn at exchange B. This is accomplished by providing the tester relays as shown in Fig. 4 with two coil windings one of which is connected via springs 5 of relay a to the third wire of the associated junction, and the other via springs of a and via springs on a cut-off relay c to one of the line conductors.

The following is a description of the operation in which a key k , for instance, is depressed and a common relay a energizes over circuit 1. If the junction is engaged, relay b' will be energized by negative from the plug third conductor over circuit 2, and 15 will glow the lamps l over circuit 3. The operator will consequently not take that junction. If it is free the lamp will not glow and the operator will plug into the jack to connect negative over circuit 4 20 through the supervisory lamps d and cut-off relay c which operates to insulate the line conductor from the tester. The manner in which the calling lamp e is caused to glow is obvious and need not be described. The 25 operator at the B exchange seeing lamp e glowing, depresses a speaking key f which connects her telephone set across the junction circuit and also closes a circuit 5 through a holding magnet i and contacts of 30 release relay m . Consequently key f will be held down. The operator at exchange B after ascertaining what connection is wanted inserts the plug p to complete the connection, and in so doing also completes circuit 6 through release relay m and clearing lamp n . m then energizes to break circuit 5 and to prepare circuit 7. The speaking key f is thus restored, and the B operator's telephone cut out of the junction circuit. At the 40 termination of the conversation, if the operator at exchange A takes down the connection but the operator at B delays doing so, and another or the same operator at A tests for an idle junction, circuit 7 will be completed at relays c and a to the second coil of tester relay b which will energize to cause lamp l to glow to indicate that it cannot be used.

Fig. 4 shows also how the tester for the 50 common or second choice group of junctions mentioned in connection with Fig. 1 is brought into use if all the junctions of the individual or first choice group be in use. If this be so, on a key k being depressed, 55 all the relays b' will be energized and circuit 8 completed through common relay a' to bring in a second tester. Each time the second tester is brought into use the fact is registered by a meter q in circuit 9 and the 60 pilot lamp r glows. If all the common group junctions are engaged this fact is registered by meter q' . It will be seen that as the second tester is not brought into use until all the first choice group junctions are 65 engaged the operators must use all idle first

choice junctions before they can use second choice junctions.

Fig. 5. As delay in operating will be caused by a junction testing "engaged" until the plug is withdrawn at the exchange B 70 and as, moreover, the out-of-use time of the junction is unnecessarily lengthened the junction circuit at exchange B may be disconnected from the cord and plug as soon as the operator at exchange A takes down 75 her part of the connection. The re-connecting of the cord and junction circuits is in the hands of the operator at B, so that an operator at A may now take up the junction (even though the plug is in a subscriber's line jack at B) and the calling lamp will glow. One way in which this is effected is as follows: A relay S is provided which normally disconnects the cord circuit from the junction line circuit and the busy- 80 potential from the plug third connection; also the calling lamp circuit 10 is completed through a back contact on the relay. It is not necessary to describe again the testing and calling by the operator at A. The 85 operator at B seeing lamp e glowing presses speaking key f to connect her telephone set across the junction circuit. Key f holds itself and closes circuit 11 through relay S , which operates and locks circuit 12 to connect the junction and cord circuits together, to disconnect e and to prepare 6 through supervisory lamp n . The operator at B 90 having ascertained the desired connection and by testing found that the line is not engaged inserts plug p in the required subscriber's line jack. Circuit 6 is therefore completed through relay m which operates and cuts circuit 5. Key f is released and 95 circuit 11 through S broken. At the termination of the conversation the operator at A takes down her part of the connection, releasing relay t and consequently breaking circuit 12 thereby releasing S . The junction and cord circuits are now again disconnected 100 and although plug p may be left in a jack the corresponding line will not test engaged; furthermore, the supervisory lamp n 105 will cease to glow, thereby indicating to operator B that she may take down her connection. If, before she does so, another connection is made at exchange A to the junction, circuit 10 will be reformed causing the calling lamp e to glow as before. 110

In the junction cord circuits no key or 115 other apparatus is shown for ringing, it being, of course, obvious that either key or keyless ringing may be employed, also the particular circuits shown are not essential to the invention, as many modifications may 120 be made to obtain similar results.

What I claim is—

1. A telephone system comprising a manual switch-board divided into sections, a group of outgoing lines allotted to each sec- 125 130

tion of the board, a further group of outgoing lines common to a plurality of sections of the board, a number of lamps, a relay associated with the test wire of each outgoing line and adapted to connect up one side of a lamp associated with such line, means for energizing the relays of busy lines, a key associated with each section, means whereby on the depression of said keys the lamps 10 are glowed on busy lines of the section group and means whereby lamps in the common group are glowed when all the lines of the section group are busy.

2. A telephone system comprising a manual switch-board divided into sections, a group of outgoing lines allotted to each section of the board, a further group of outgoing lines common to a plurality of sections of the board, a number of lamps, a 15 relay associated with the test wire of each outgoing line and adapted to cut off a wire from the talking circuit, a key associated with each section, a switching relay adapted to be energized on the depression of a key, a number of tester relays, means whereby a 20 tester relay is connected in parallel with each of the third conductor relays, means for energizing the tester relays and third conductor relays of busy lines to glow lamps 25 in the section group and means whereby lamps in the common group are glowed when all the lines of the section group are busy.

3. A telephone system comprising a man-

ual switch-board divided into sections, a group of outgoing lines allotted to each section of the board, a further group of outgoing lines common to a plurality of sections of the board, a number of lamps, a 35 relay associated with the test wire of each outgoing line and adapted to cut off a wire from the talking circuit, a key associated with each section, a switching relay adapted to be energized on the depression of a key, a number of tester relays, means whereby a 40 tester relay is connected in parallel with each of the third conductor relays, jacks at each end of the lines, plugs for said jacks and means for energizing the tester relays and third conductor relays of busy lines to 45 glow lamps in the section group and means whereby lamps are glowed on busy lines after a plug has been removed from the outgoing jack of a line and until the plug is also removed from the jack at the far end of the line.

4. A telephone system comprising a manual switch-board divided into sections, a group of first choice junction lines allotted individually to each section, a group of second choice junction lines accessible in a plurality of sections, a number of lamps, keys for connecting said lamps to different sets of junction lines and means whereby, on the depression of said keys, the lamps are 50 glowed on busy lines.

WILLIAM AITKEN.
